UNITED STATES PATENT OFFICE.

ALBERT W. WAGNER, OF TERRE HAUTE, INDIANA.

DOOR-HANGER.

1,202,927.

Specification of Letters Patent. Patented Oct. 31, 1916.

Application filed April 3, 1916. Serial No. 88,509.

To all whom it may concern:

Be it known that I, ALBERT W. WAGNER, a citizen of the United States, residing at Terre Haute, in the county of Vigo and State of Indiana, have invented new and useful Improvements in Door-Hangers, of which the following is a specification.

My invention relates to improvements in door-hangers, the principal objects being to provide a hanger-track adapted to receive the conventional type of truck, and which, while including an efficient water-shed for protecting the truck and upper part of the door as well as the space between the latter and the truck from the admission of moisture, will, nevertheless, permit of very considerable lateral movement or swing of the door—a feature of considerable importance in structures of this kind.

Other objects of minor importance concerning the invention will hereinafter appear, and the novel features thereof will be particularly pointed out in the appended claims.

Referring to the drawings: Figure 1 is a fragmentary view in front elevation of a door-hanger embodying my improvements; Fig. 2 is a fragmentary detail in perspective of my improved water-shed; Fig. 3 is a vertical transverse sectional view of Fig. 1, the door being shown as swung outward; and Fig. 4 is a view similar to Fig. 3, with parts broken away and the door shown in its normal or vertical position; Fig. 5 is a view similar to Fig. 1, but illustrating a modified construction; Fig. 6 is a similar view to Fig. 1, but illustrating a second modified construction; Fig. 7 is a vertical sectional view of Fig. 5; and Fig. 8 is a similar view, with parts broken away, of Fig. 6.

Similar numerals of reference indicate similar parts in all the figures of the drawings.

The housing for the accommodation of the truck, as will hereinafter appear, may be conveniently formed by suitable dies, and may be said to comprise three parts, namely: the upper attaching-flange 1, the intermediate housing 2, and the lower track 3, these parts preferably all being formed in one integral piece. The housing 2 may be of any desired shape in cross-section that is best designed to receive and protect the truck 4, which latter, it will be understood, may be of any well-known conventional design and construction but in any event comprising the

usual wheels 5, and goose-neck hanger 6, the latter being bolted to the door 7, as at 8, for which purpose the goose-neck hanger may terminate in a securing-plate 9. The upper wall of the housing is vertically disposed to form the attaching-flange 1, heretofore mentioned, and the lower edge of the housing is bent inwardly and upwardly, as at 10, to a point above its lower edge, after which it may be recurved upon itself in the arc of a circle coincident with the grooves of the wheels 5, thereby constituting a track-rail 11, cylindrical in cross-section and adapted to support the truck. This track, it will be observed, being only partly cylindrical in cross-section, produces at its front but in rear of the lower edge of the housing 2, an elongated longitudinally disposed opening or slot 12, the lower edge of which forms a stop-shoulder 13, which, as will hereinafter appear, performs an important function in the operation of the device.

15 designates the water-shed, the same being preferably bent as shown, and formed conveniently of sheet-metal. At the upper edge of the shed a cylindrical longitudinally disposed rib 16, is formed, and such rib is made of a diameter as to adapt it to be inserted endwise within the tubular track 3, in which position the shed will project through the slot or opening 12 and beyond the same to form a cover or water-shed depending in front of the usual space necessarily occurring between the upper edge of the door and the housing and prevent the admission of moisture.

It will be seen that as a matter of fact the water-shed is hingedly connected to the lower edge of the housing, and is capable of swinging with the door, its movements being limited only by the width of the slot 12. When the door is hanging vertically, the water-shed is prevented from contact therewith by the presence of the stop-shoulder 13, the latter being so located with relation to the door as to support the water-shed in an inclined position out of contact with the door. In this manner chafing between the door and the water-shed during the sliding of the door is avoided. As the door is swung out for any purpose, the water-shed likewise swings to accommodate this movement of the door, and even in such position, performs its useful and intended function of a water-shed.

In the drawings I have merely illustrated

and described some of the preferred forms of my invention, but I desire to be understood as not limiting the invention to the details herein. Heretofore, water-sheds 5 have been provided in structures of this nature, but, as far as my knowledge extends, they have merely been rigid continuations of the housing, so that the swinging movement, so desirable, has been possible only 10 to a very limited extent. By my invention, however, the door may be swung as far as is ever necessary for any purpose whatever, the water-shed described readily accommodating itself to such movement. The water- 15 shed may be of any shape desired in cross-section found best adapted for the purpose of successfully shedding water in any of its positions, and it may be connected to the housing in any desired manner that will 20 permit of it swinging with the door. Where the hanger is employed indoors, no water-shed is necessary, and, of course, may be omitted.

Referring now to Figs. 5 to 7 inclusive, 25 it will be seen that I have somewhat varied the construction or manner of supporting the water-shed by utilizing auxiliary devices for this purpose. In the constructions illustrated in these last mentioned figures a series of supporting-strips 17 and 17^a, are employed. These strips are similar at their lower ends in both constructions, in that they are disposed under and slightly in rear of the lower curved edges of the housings, 30 as indicated at 18, at which points they are preferably riveted to the housings as at 20, and beyond which they are bent or curved, as at 19, so as to form one member of a hinge-like joint for supporting in a movable manner the water-shed 15, as heretofore described. In Fig. 7 the supporting-strips 17 are extended above the housing proper, terminating at points opposite the attaching-flange 1. This flange as well as the strips 35 17, are provided with openings, and through each pair of such openings is passed a lag-screw 21, the threaded end of which enters the wall of the building. These lag-screws, in this construction, take the place of the usually employed attaching-screws for the purpose of supporting the door-hanger in its working position, and in addition to this function, it will be seen that by feeding the 40 screws farther in the wall of the building, the strips 17 will act as levers for drawing the lower edge of the housing outward. Of course a reverse movement of the lag-screws will have a reverse effect upon the housing. In this manner the housing may be given 45 proper adjustment with relation to the building. In Fig. 6 the construction is the same as I have described, with the exception that the strips 17^a are not extended to form levers but terminate above the lower edge of the housing, at which points they

are riveted, as at 20. In both of these constructions it is preferable that the goose-neck 6 be made adjustable, that is to say, formed of two sections 6^a and 6^b, pivoted together as at 6^c. With the goose-necks 70 thus formed the wheels of the truck may always remain stationary, and yet, at the same time, the door 7 may be swung outward. It will be seen that, in either construction, a water-shed hinged either directly or indirectly to the lower edge of the housing will not interfere with the swinging of the door.

While it is highly probable that in any instance where a water-shed is desirable, an 80 efficient housing is likewise desirable, yet there may be instances where the housing is not necessary owing to the fact that the track is supported within the door-way and protected to some extent thereby, and yet 85 the water-shed might be useful at a lower point in the structure for the purpose of covering the opening between the track and the upper edge of the suspended door. I do not, therefore, wish to be understood as 90 limiting the application of my flexible water-shed to a housing in which the track is formed as a part or independent thereof, for the housing may be entirely omitted and the water-shed suspended in any flexible 95 manner either from the track or any other suitable support.

Having described my invention, what I claim is:

1. In a door-hanger, the combination with 100 a housing provided with attaching-means and an inclosed track, a truck movable on the track, and a door suspended from the truck, of a water-shed swingingly supported from the housing below the track and depending in front of the door.
2. In a door-hanger, the combination with 110 a housing provided adjacent its lower edge with a tubular track, of a water-shed having its upper edge bent to engage said track 110 and loosely swing therefrom.
3. In a door-hanger, the combination with 115 a housing provided adjacent its lower edge with a tubular track, of a water-shed having its upper edge bent to engage said track and 115 loosely swing therefrom, and means for limiting the swinging movements of the water-shed.
4. In a door-hanger, the combination with 120 a housing having its lower edge provided with a tubular track having a reduced opening at its front, of a water-shed having a tubular rib mounted in the track and extending through the opening.
5. In a door-hanger, the combination with 125 a housing having its lower edge bent to form an internal tubular track terminating in the stop-shoulder and forming the reduced opening of a water-shed having its upper edge bent to form the tubular rib 125

mounted in the track and extending through the opening.

6. In a door-hanger, the combination with a housing having the intermediate truck receiving portion and above the same bent to form an attaching-flange and at its lower edge bent to form the tubular track having the longitudinal opening at its front, of a truck located on the track, a door connected to the truck, and a water-shed having its upper edge bent to form a rib loosely con-

nected with the track and extending through the opening therein and depending in front of said door.

In testimony whereof I have signed my name to this specification in the presence of two subscribig witnesses.

ALBERT W. WAGNER.

In the presence of—

W. S. DUVALL,
E. ELLIS.
